WILLIAM WHEELER
INVENTOR

BY *Victor J. Evans*

ATTORNEY

UNITED STATES PATENT OFFICE

WILLIAM WHEELER, OF RICHMOND, KENTUCKY, ASSIGNOR OF ONE-HALF TO WILLIAM SAMUEL DE BARDELEBEN, OF RICHMOND, KENTUCKY

RING

Application filed July 23, 1929, Serial No. 380,396. Renewed March 25, 1932.

The object of this, my present invention, is the production of a finger ring in which the box on the shank of the ring is provided with spring means for engaging shoulders on stones or settings which are inserted in the box.

A further object is the provision of a finger ring that is designed to be cheaply constructed and marketed, that shall include a mount and stones or settings for the mount, each designed to be individually sold from the same counter, the stones or settings having different marks or letters on the outer faces thereof, so that certain desired stones may be purchased with a mount and inserted and retained in the box or the mount so that the purchaser will possess himself of either a signet ring or a ring which will bear the insignia of a lodge or fraternity to which the purchaser belongs.

To the attainment of the foregoing the invention consists in the improvement hereinafter described and definitely claimed.

In the drawings:
25 Figure 1 is a side elevation of the improvement.

Figure 2 is an end elevation thereof.

Figures 3 and 3a illustrate in plan different types of stones or settings.

30 Figure 4 is an enlarged longitudinal sectional view through the box of the finger ring.

Figure 5 is a substantially similar view but showing the manner in which a stone or setting is inserted in the box.

35 Figure 6 is a view substantially similar to Figure 4 but illustrating a slight modification.

Figure 7 is a sectional perspective view of the construction disclosed by Figure 6.

40 Figure 8 is a perspective view of one of the stones or settings.

My improved finger ring construction is especially designed for use by members of high school fraternities and is designed to provide a cheap article of commerce in which mounts and separate stones or settings are arranged on the same counter of a jeweler or in a department store, so that a purchaser or the like may likewise purchase stones or

settings that have letters or indicia on the outer face thereof that will correspond to the insignia of the fraternity of which the purchaser of both the mount and ring belongs.

55 The mount and ring is of substantially ordinary construction, the same including the usual shank 1 and the box 2 for the setting. The box 2 in the present instance is of substantially rectangular formation, two of the opposed inner walls thereof being formed with vertically-extending recesses or depressions 3 and to the inner walls, adjacent to the upper ends of the said depressions there are fixed by means 4 the ends of flat but arched springs 5. The free ends of the springs will normally be projected into the box.

60 The setting may be made up of any desired number of stones, each having on its outer face a letter or insignia. As all of the stones are of a similar construction a detail description of one will be taken as applicable to the remainder. In this connection it may be necessary to state that the box 2 is of a 65 size to contain at least three stones of the desired width or four stones, two of which are of a greater width than the others as disclosed by Figure 3a of the drawings. In this instance the outer stones are in the nature 70 of ornaments, while the central stones have on their outer faces the letters or insignia of the fraternity of the purchaser of the stone or setting. Also the stones are of a depth 75 approximately equaling that of the box 2. Each stone has its ends cut inwardly from 80 points adjacent to its outer corners to provide its inner corners with shoulders or ledges 6 and these shoulders are designed to be contacted by the ends of the springs 5 85 when the stones are inserted in the box.

90 In Figures 6 and 7 the depressions 3' are formed on one of the opposed inner walls of the box and the second opposed inner walls are formed with notches 7 of the same length 95 but of a greater width than that of the depressions 3'. In the depressions there are fixed the upper ends of the arched springs 9 and the outward movement of the said 100 springs is limited by the contact of the outer

walls provided by the depressions while in other respects the ring construction is similar to that above set forth as are also the settings received in the box 1.

5 Having described the invention, I claim:
A finger ring comprising a ring portion having a chamber provided with recesses in oppositely disposed walls to provide inner and outer shoulders extending substantially 10 the full length of said walls, tension plates secured in the recesses adjacent the outer shoulders and projecting outwardly beyond the lower shoulders, said chamber having recesses in the other walls and communicating 15 with the recesses of the first mentioned walls to provide shoulders for limiting the movement of the tension plates outwardly of the first mentioned recesses, a setting located in the chamber, and shoulders on said setting 20 engaged by the free edges of the plates.

In testimony whereof I affix my signature.
WILLIAM WHEELER.
